UNITED STATES PATENT OFFICE.

JULIUS WILLIAM CONRADT, OF MIDDLETOWN, CONNECTICUT.

HARNESS FOR HORSES.

SPECIFICATION forming part of Letters Patent No. 313,850, dated March 17, 1885.

Application filed December 18, 1884. (No model.)

To all whom it may concern:

Be it known that I, JULIUS WILLIAM CONRADT, of Middletown, Connecticut, have invented a certain new and useful Improvement 5 in Harness for Horses, of which the following description and claim constitute the specification, and which is illustrated by the accompanying sheet of drawings.

This invention is an attachment of the saddle of a harness in the place of the check-hook, and its function is to enable the driver to uncheck the horse without leaving his seat in the carriage, and also to automatically check the horse at different elevations of the head after 15 the purpose of unchecking has been accomplished.

Figure 1 of the drawings is a side view of my invention ready for attachment to a harness. Fig. 2 is a side view of the same with 20 the side plate and the parts exterior thereto removed. Fig. 3 is a rear elevation of the invention as seen from a point on the right-hand side of Fig. 1. Fig. 4 is a front elevation of a harness-saddle with the invention attached thereto. Fig. 5 is a perspective view of the 25 forward half of a horse properly harnessed with a harness containing my invention.

A is the case of the apparatus, consisting of a disk and a peripheral flange integral therewith. The flange is provided with the opening B, and is fastened to the standard C, which standard is attached to the saddle of a harness by the bolt D and the nut E. The arbor F is rigidly fixed in the axis of the case 35 A, being attached to the disk by having its squared end fitted to a corresponding recess in the disk. The side plate, G, is held rigidly against the edge of the flange of the case I by means of a hole in the center of the plate opposite to the axis of the arbor F, and by means 40 of the screw H, which fastens the plate to the end of the arbor.

The inner case, I, is a flanged disk of smaller diameter and narrower periphery than case A. 45 Its flange also extends in the opposite direction from the other, and its disk has a round hole in its center for the reception of the arbor F, upon which it revolves.

The coiled spring J is placed within the in-

ner case and around the arbor, and has its 50 outer end fixed to the case and its inner end fixed to the arbor.

The strap K is coiled several times around the inner case, to the outside of the flange of which it is fastened at its inner end, and its 55 outer end projects from the opening B in the flange of the outer case, A, and is provided with a suitable hook or other device for convenient attachment to the check-rein of a harness. The outer side of the inner case is provided with the shallow socket L, for the reception of the inner end of the dog M, which dog reciprocates through the tubular projection N of the plate G.

A spiral spring, O, encircles that part of the 65 dog which is within the tubular projection, and is so adjusted as to gently carry the end of the dog into the socket L. The outer end of the dog is provided with the shank P, extending backward therefrom, and the rear end 70 of the shank is provided with the ring Q, which ring is substantially parallel with the bolt D when viewed as in Fig. 1, but is carried far enough to the left of that bolt to be substantially on a line with one of the 75 rein-rings of the saddle, as shown in Figs. 3, 4, and 5.

The mode of operation of my invention is as follows: The coiled spring J draws the strap K into the outer case, A, and around the inner case, I, and the spiral spring O holds the dog M into engagement with the socket L. Thus the hook or other termination of the strap K acts as a fixed check-hook upon the check-rein, which is attached thereto. When the driver 85 wishes to uncheck the horse, to allow it to drink by the wayside, or to lower its head while ascending a hill, he pulls his left-hand rein gently to the left, and thus withdraws the dog M from the socket L. Then the horse 90 will lower its head against the action of the coiled spring J. Afterward, when the head is raised, the spring J will draw in the strap K until it reaches its inmost limit, when the driver, by moving the left-hand rein back to 95 its normal position, allows the dog M to again engage with the socket L; or, by sooner releasing the ring Q from the pressure of his

rein, the driver may sooner allow the dog to engage with the socket, and thus may check the horse's head at a less elevation than before.

The dog M may be managed by a cord or strap of its own extending to the hand of the driver, if desired, and the apparatus may be modified in other particulars without changing its essential character.

I claim as my invention—

In a check-rein holder, the combination of 10 the case I, having the socket L, with the dog M, the spring O, and the plate G, provided with the projection N, all substantially as described.

JULIUS WILLIAM CONRADT.
